L. D. GREGG.

SUPPORT AND LOCK FOR GATES.
APPLICATION FILED NOV. 27, 1918.

1,318,550.

Patented Oct. 14, 1919.

UNITED STATES PATENT OFFICE.

LOUIS D. GREGG, OF HACKENSACK, NEW JERSEY, ASSIGNOR TO THE GREGG COMPANY, LIMITED, OF NEWBURGH, NEW YORK, A CORPORATION OF NEW YORK.

SUPPORT AND LOCK FOR GATES.

1,818,550.

Specification of Letters Patent.

Patented Oct. 14, 1919.

Application filed November 27, 1918. Serial No. 284,440.

To all whom it may concern:

Be it known that I, LOUIS D. GREGG, a citizen of the United States of America, and a resident of Hackensack, New Jersey, have 5 invented a new and useful Improvement in Supports and Locks for Gates, which invention is fully set forth in the following specification.

This invention is intended primarily for 10 maintaining in upright closed position the downward-swinging door or drop-gate at the side or end of a car-body, but is applicable for other service.

When a drop-gate car is filled with a load 15 of loose material (such as coal, gravel, stone, etc.); not only is it essential that the gate be held securely closed, but it is important that it can be readily released to permit the discharge of the load; yet the outward 20 pressure exerted against the gate by the load tends to bind the releasable catches heretofore used, so as to render difficult the release of the catch.

The object of the present invention is to 25 provide a secure gate-support or locking-means, which can be readily released. The main feature of the invention comprises a bar detachably secured, intermediate its ends, to the gate or other hinged member, 30 to extend across the pivot of the gate when in closed position, so that the two ends of the bar will bear respectively against the gate and against the car-sill or other relatively-stationary body. Among other features of the invention are: a preferred form 35 of detachable support or disengageable connecting-means for said bar; means for attaching the bar permanently yet loosely to the gate; and means for limiting the outward swing of the thus-attached bar, when 40 the gate is opened. The various features of the invention will be more fully pointed out and defined in the claims.

Although the invention is susceptible of 45 expression in various forms, yet for the sake of illustration a preferred embodiment will now be set forth as applied to the hinged drop-side of an ordinary car-body.

In the annexed drawings, illustrating the 50 preferred embodiment:

Figure 1 is a perspective view of a portion of a car-body showing the drop-gate closed, and the new supporting-bar in locked-position,—the unlocked position of said bar being indicated by dotted lines;

Fig. 2 is a face elevation of the structure of Fig. 1; and

Fig. 3 is a side elevation, showing the gate fully opened.

In these drawings, 1 represents a relatively-stationary body, such as the under-frame of a car, which affords the vertical bearing-surface 2. 3 is the outwardly-swinging side-gate or drop-door of the car. 4 is one of the two or more stakes or cleats 5 or battens by which the swinging member or gate is hinged at its bottom, as at 5, to the car-body. As shown, this stake may consist of two L-shaped or angle-bar members, placed back to back and firmly secured to 70 the gate with a vertical channel between the two members. 6 is the supporting-bar whose upper and lower ends bear respectively against the upper portion of the stake and the stationary bearing-surface 2; and this 75 bar is here shown as a T-shaped bar with its T-head outside. Intermediate the ends of this bar, and intermediate between the hinged end and the free end of the stake, and adjacent the hinge, are located the two 80 disengageable connecting-members which constitute a detachable support for the bar. As shown, these members consist respectively of a stud 7 carried by the stake and protruding on both sides thereof, and two 85 duplicate hooks 8 carried on each side of the supporting-bar, to engage respectively over the two ends of the stud. But it is obvious that the hooks might be inverted, and mounted on the stake 4, and the stud 90 on the bar 6; or a single hook and stud might be employed, or a staple might be used instead of a stud.

Preferably, yet not necessarily, the upper end of the supporting-bar may be permanently but loosely connected to the stake, as by means of a slot and pin, so as to permit slight vertical movement of the bar; and, in that case, as here shown, the upper portion of the flange or T-head of said bar may 100 be cut away to leave shoulders 9, and the flat end of the bar located in the channel between the two stake-members, and the latter slotted vertically at 10 to receive the pivot-pin 11 carried by the bar. It is obvious however, that the slot might be in the bar, and the pin carried by the stake; or that any loose attachment (other than slot and pin) might be employed.

After the gate has been swung up into 110

closed position and the catch-members 7—8, engaged (as in Fig. 1), it will be seen that the supporting-bar 6 constitutes a lever of the first order, with a detachable support 5 upon stud 7; and that any outward movement of the gate against that end of the lever is prevented by the opposition of the bearing-surface 2 against the other end of said lever. In order to release the gate, it 10 is only necessary to raise the several supporting-bars or levers 6 sufficiently to disengage the hooks from their respective studs 7,—as by a smart blow, with a hammer, upon the lower end of each of the supporting-bars. This drives the bars upward (which 15 is permitted by their slot-and-pin connection), and disengages the hooks (as indicated by dotted lines in Fig. 1); whereupon the gate will swing out, and drop down into 20 the position indicated by Fig. 3. Preferably the supporting-bar is bent, as shown, so that merely its end-portions will abut against the swinging-member and the relatively-stationary surface, in order to diminish the frictional 25 resistance to the longitudinal movement of the bar, in disengaging the catches.

When the bar is thus unlatched, the shoulders 9 serve as a stop, abutting against the outer edges of the stake-members, to prevent 30 the bar from swinging out more than (say) 90 degrees; and this insures that the lower end of the bar will not strike the ground and prevent the gate from swinging down freely, into the position indicated by Fig. 3.

35 The preferred embodiment of the invention has thus been set forth in considerable detail, but only for the sake of clearness; since the invention is not limited to the particular construction and arrangement of 40 parts disclosed, but can obviously be expressed in various other forms. For example, instead of using the stud-and-hook connection set forth, the supporting-bar may be maintained with its two ends bearing 45 against the closed gate and against the bearing-surface 2 respectively, by any suitable means which will hold the bar firmly in position and can be readily disconnected.

The invention having been thus fully described, what is claimed is:

50 1. The combination of a relatively-stationary body such as a car-sill presenting a bearing-surface, a swinging member such as a car-gate pivoted thereto, and a bar on the outer side of said member and detachably connected thereto intermediate the ends of said bar, said ends abutting respectively against said member when in closed position and against said surface.

60 2. The combination of a relatively-stationary body such as a car-sill presenting a bearing-surface, a swinging member such as a car-gate pivoted thereto, a bar whose two ends abut respectively against said member 65 when in closed position and against said sur-

face, and disengageable connecting-members located intermediate the ends of said bar and carried respectively by said gate and said bar.

3. The combination of a relatively-stationary body presenting a bearing-surface, a swinging member pivoted thereto and carrying near its pivot one of two catch-members, a bar carrying intermediate its ends the complementary catch-member and abutting at 75 its two ends against said surface and against said swinging member when closed, said bar being longitudinally movable to engage and disengage said catch-members.

4. The combination of a relatively-stationary body presenting a bearing-surface, a swinging member pivoted thereto and carrying near its pivot one of two catch-members, a bar loosely connected at one end to the swinging member so as to permit vertical 85 movement and carrying intermediate its ends the complementary catch-member and abutting at its two ends against said surface and against said swinging member when closed. 90

5. The combination of a relatively-stationary body presenting a bearing-surface, a swinging member pivoted thereto and carrying near its pivot a stud, and a bar carrying intermediate its ends a hook adapted to engage said stud, said bar abutting at its two ends against said surface and against said swinging member when closed, and being longitudinally movable to engage and disengage 95 said hook and stud. 100

6. The combination of a relatively-stationary body presenting a bearing-surface, a swinging member pivoted thereto and carrying near its pivot a catch-member, a bar having at one end a slot-and-pivot connection 105 with said swinging member, and a complementary catch-member carried intermediate the ends of said bar and adapted to engage the first-named catch-member, said bar abutting against said surface and being longitudinally 110 movable to engage and disengage said catch-members.

7. The combination of a relatively-stationary body presenting a bearing-surface, a swinging member pivoted thereto and carrying near its pivot a catch-member, a bar whose upper end is loosely pivoted to said swinging-member, means to limit the outward swing of said bar, and a catch-member carried intermediate the ends of said bar 120 and adapted to engage and disengage the first-named catch-member, the two ends of said bar adapted to abut respectively against said surface and against said swinging member when closed. 125

8. The combination with a relatively-stationary body presenting a bearing-surface and a second body hinged to swing outward therefrom, of a bar entirely outside of both of said bodies and adapted to bear against 103

them both when the hinged body is closed, and disengageable connecting-members secured respectively to said bar and said hinged body for detachably holding said bar 5 firmly against said bodies to maintain the hinged body in closed position.

9. The combination with the underframe of a car-body and the gate hinged thereto to swing outwardly, of a stake-bar attached at 10 its upper end to said gate by pivot-and-slot connection and bearing at its lower end

against said underframe, and disengageable locking-members located intermediate the ends of said bar, and carried respectively by said gate and said bar, for maintaining the 15 ends of said bar in bearing-contact against said gate and underframe, in order to support said gate in closed position.

In testimony whereof I have signed this specification.

LOUIS D. GREGG.
